The ornamental design for a clothes hanger, as shown and described.

DESCRIPTION

FIG. 1 is a bottom-front perspective view of a clothes hanger showing our new design;

FIG. 2 is a top plan view thereof;

FIG. 3 is a bottom plan view thereof;

FIG. 4 is a rear elevational view thereof;

FIG. 5 is a front elevational view thereof;

FIG. 6 is a left side elevational view thereof;

FIG. 7 is a right side elevational view thereof;

FIG. 8 is a bottom-left perspective view thereof; and,

FIG. 9 is a rear perspective view thereof, wherein the clothes hanger is illustrated with a T-shirt hung therefrom to illustrate an exemplary use of the clothes hanger, the T-shirt shown in broken lines forms no part of the claimed invention.

The broken line portions of the drawing figures are included to show unclaimed subject matter only and form no part of the claimed design. In particular, the hanger end caps and the T-shirt shown in broken lines form no part of the claimed invention.
